(57) **CLAIM**

The ornamental design for a work light, as shown and described.

DESCRIPTION

FIG. 1 is a front view of a work light showing my new design.

FIG. 2 is a rear view thereof.

FIG. 3 is a left side view thereof.

FIG. 4 is a right side view thereof.

FIG. 5 is a top view thereof.

FIG. 6 is a bottom view thereof.

FIG. 7 is a front side perspective view thereof.

FIG. 8 is a rear side perspective view thereof.

FIG. 9 is an enlarged detail view of area 9 shown in FIG. 3.

FIG. 10 is an enlarged detail view of area 10 shown in FIG. 5.

FIG. 11 is a perspective view thereof, shown in a folded state; and,

FIG. 12 is another perspective view thereof, shown in a folded state.

The broken lines encircling the enlarged views show the boundaries of the enlarged views and form no part of the claim.

The broken lines in the drawings depict portions of the work light and form no part of the claimed design.

1 Claim, 12 Drawing Sheets
